UNITED STATES PATENT OFFICE.

CHARLES J. WEEKS, OF JACKSONVILLE, FLORIDA.

OIL-COOLING DEVICE.

Application filed February 5, 1923. Serial No. 617,135.

To all whom it may concern:

Be it known that I, CHARLES J. WEEKS, a citizen of the United States, residing at Jacksonville, county of Duval, and State of Florida, have invented certain new and useful Improvements in Oil-Cooling Devices, of which the following is a specification.

My invention relates to oil cooling devices for engines, such as contain an oil well or chamber. The main and particular objects and advantages of my invention are, to provide an effective oil cooling device of very simple construction, of few parts, and comparatively inexpensive to manufacture, which will function automatically whenever, and as long as, the engine is in operation.

These and various other objects and advantages will be clearly understood from the following description and the accompanying drawing of a preferred embodiment of my invention, but it will be readily understood that various modifications might be made without departing from the scope of my invention.

Fig. 1 is a side view, showing the cooling devices attached to the side plates of an automobile engine.

Fig. 2 is a cross-sectional plan view of Fig. 1, taken on the line 2-2 on Fig. 1, and showing the side plates of the engine only.

Fig. 3 is a side view of a modification.

Fig. 4 is a plan view of Fig. 3.

Figs. 2, 3 and 4 are all drawn to a larger scale than Fig. 1.

Referring first to Figs. 1 and 2, 1 shows an automobile engine, 2 the side plates on same, and 3 the fan usually mounted ahead of the engine. The cooling devices, which are shown at 4, each consists of an air duct 5 which is closed on all sides but open at the front so as to allow air to enter the openings 6. The openings 6 may be of any shape, for example semicircular, but are here shown as rectangular.

Inside the air ducts and near their rear ends, openings 7 are cut in the plates 2, these

openings are covered with finely woven, wire mesh screens 8. Shutters 9, by means of which the openings 6 may be closed, are also provided.

Referring now to the modification shown in Figs. 3 and 4, 10 are the engine side plates. In this case four openings 11 are cut in the side plates, and in place of the separate air ducts a manifold air duct 12 is substituted. This manifold air duct is tapered and has outlets 13 communicating with the openings 11 in the side plates. It is also provided with an enlarged intake opening 14 which is covered with wire mesh 15.

The device operates in the following manner: When the fan revolves or, as in the case of engines mounted on vehicles, the vehicle moves forward, air is forced by either or both of these actions into the air ducts and through the openings in the side plates into the oil chamber, thus cooling the oil contained therein. To prevent dust or other foreign matter from entering with the air the screens 8 are provided. As it might be undesirable during very cold weather to cool the oil, the shutters 9 are provided so that the air ducts may be closed.

Having thus described my invention and its operation, what I claim as new and desire to protect by Letters Patent is:

In an oil cooling device of the class described; a plurality of openings formed in the side plates of the engine to which the device is attached, at or near its oil chamber; all of said openings communicating with a forwardly extending air duct; and said air duct so proportioned in size that an equal amount of air is caused to flow through each of said openings when the device is in operation.

In testimony whereof I, CHARLES J. WEEKS have signed my name to this specification in the presence of two subscribing witnesses this 24th day of August, 1922.

CHARLES J. WEEKS.

Witnesses:

Mrs. C. J. WEEKS,
HENRIK J. SCHMIDT.
